UNITED STATES PATENT OFFICE

125,306

DESIGN FOR A SEWER CLEANER

William M. Emery, Cleveland Heights, Ohio, assignor to The Oster Manufacturing Company, Cleveland, Ohio, a corporation of Ohio

Application May 18, 1940, Serial No. 92,445

Term of patent 7 years

To all whom it may concern:

Be it known that I, William M. Emery, a citizen of the United States and a resident of Cleveland Heights, Cuyahoga County, Ohio, have invented a new, original, and ornamental Design for a Sewer Cleaner, of which the following is a specification, reference being had to the accompanying drawing, forming a part thereof.

In said drawing:

Fig. 1 is a view in perspective of the top, front,

and side of a sewer cleaner embodying my new design; and

Fig. 2 is a view in perspective showing the top, rear, and side thereof.

The side not shown is substantially like the side shown.

I claim:

The ornamental design for a sewer cleaner, as shown and described.

WILLIAM M. EMERY.
